UNITED STATES PATENT OFFICE.

ATLEE W. LANE, OF PHILADELPHIA, PENNSYLVANIA.

DESIGN FOR A SHADE-PENDANT.

SPECIFICATION forming part of Design No. 12,265, dated May 17, 1881.

Application filed August 16, 1880. Term of patent 7 years.

To all whom it may concern:

Be it known that I, ATLEE W. LANE, a citizen of the United States, residing at Philadelphia, Pennsylvania, have invented and produced a new and original Design for Shade-Pendants, of which the following is a specification.

My design for a window-shade pendant is shown in the accompanying drawings, the three views of which represent slightly-modified forms of my design.

In Figure 1, A represents the lower slat of the shade, from which hang the two vertical cords or chains *a a*, carrying a horizontal bar, B, which is parallel with and a short distance below the slat A. On each end of the bar B, outside of the point of connection of the cord or chain *a*, is formed an ornamental knob. The shape of these knobs may vary. For instance, the knob shown in Fig. 1 is in the form

of an acorn, that in Fig. 2 resembles a spear-head, while that in Fig. 3 is a sphere of greater diameter than the bar. Between the cords or chains *a* is a looped cord or chain, D, which may be in the form of a single loop, as in Figs. 25 1 and 2, or a series of loops, as in Fig. 3.

I claim—

The within-described design for a shade-pendant, said design comprising the vertical cords or chains *a a*, the horizontal bar B, and the looped cord D, all substantially as shown and described.

In testimony whereof I have signed my name to this specification in the presence of two subscribing witnesses.

ATLEE W. LANE.
